DESIGN FOR A MONOGRAMMED NECKTIE FASTENER OR SIMILAR ARTICLE

Charles Silverman, Providence, R. I.

Application March 25, 1939, Serial No. 83,824

Term of patent 3½ years

To all whom it may concern:

Be it known that I, Charles Silverman, a citizen of the United States, residing at Providence, in the county of Providence and State of Rhode Island, have invented a new, original, and ornamental Design for a Monogrammed Necktie Fastener or Similar Article, of which the following is a specification, reference being had to accompanying drawing, forming part thereof.

I claim:

The ornamental design for a monogrammed necktie fastener or similar article, as shown.

CHARLES SILVERMAN.
